ALFRED H. COHEN, OF OAKLAND, CALIFORNIA.

METHOD AND APPARATUS FOR PRODUCING OSCILLATING CURRENTS OF HIGH FREQUENCY.

1,243,043.

Specification of Letters Patent. Patented Oct. 16, 1917.

Application filed December 8, 1914. Serial No. 876,154.

To all whom it may concern:

Be it known that I, ALFRED H. COHEN, a citizen of the United States, residing at Oakland, county of Alameda, State of California, whose post - office address is 1440 Twenty-ninth avenue, have invented a new and useful Improvement in the Methods and Apparatus for Producing Oscillating Currents of High Frequency, of which the following is a specification.

This invention relates to the production of high frequency oscillating currents, for use particularly in wireless communication and the transmission of power.

15 Among the objects sought to be accomplished are, to produce an apparatus of this character that is simple in construction and operation;

That will maintain, as nearly as may be, a 20 constant and persistent oscillating current;

That provides for the circulation of a liquid having slight conductivity, between the faces of the electrodes in the oscillator;

That provides means for visual examination, at any time, of the operation of the 25 spark gap between the electrodes;

That provides means for quickly closing the spark gap, and the opening of the spark gap a predetermined distance;

30 That is adaptable for use under conditions of constant vibration, sudden shock, change of position and other conditions to be met in marine service, on warships for instance during heavy gun fire; in land service on railroad trains, transportation wagons, horse-back and other extreme conditions, met with particularly in military service.

Other objects and advantages will appear as the description progresses. In the drawings accompanying and forming part of the 40 present specification, to which like reference characters have been applied, a simple form of putting this invention into practice is shown. I do not wish to be understood as 45 confining this invention to the disclosures made in said drawing and description, as many variations may be introduced, within the spirit of this invention, as defined in the claims succeeding the said description.

50 In the one sheet of drawings:

Figure 1 is a side elevation, partially in cross section on the line I—I, Fig. 2, of an

oscillator constructed in accordance with this invention.

Fig. 2 is a cross section of the same taken 55 on the line II—II, Fig. 1.

Fig. 3 is a detail in front elevation of the metallic electrode, showing the ports there-through for circulating the liquid, between 60 the electrodes.

In detail the construction illustrated in the drawings includes the electrode 1, having a smooth, level plane, sparking surface. This electrode has the hollow chamber 2 cored therein, with which the inlet and outlet pipes 3 and 4 communicate. These pipes are connected with a supply tank 5 filled with a cooling liquid adapted to circulate through the chamber 2, for the purpose of removing the heat created by the spark and 65 radiated by the electrode 1. Thermo-siphon circulation is usually sufficient for the circulation of this cooling liquid, but the circulation can be rendered more positive by the addition of the force pump 6. The electrode 70 1 is surrounded by an annular groove into which the glass ring 7 is cemented.

The electrode 8 is preferably of carbon, coinciding in outline with the active face of the metallic electrode 1. This carbon electrode is embedded in the metallic holder 9, having flanged edges 10 extending to near the sparking surface of the electrode, which has a lateral flange overhanging the thickness of the flange 10. The flange 10 is annularly 85 grooved to receive the packing 11, entirely encircling the electrode 8 and its holder 9, hermetically packing the electrode 8 within the glass ring 7. The attenuated lip 12 of the packing is forced against the wall of the 90 glass ring 7, by the pressure of the liquid confined between the two electrodes and the encircling glass wall of the ring 7.

The space 13 between the electrodes 1 and 8 constitutes the spark gap, that is hermetically surrounded by the glass ring 7, as described. The container 14 is adapted to contain a liquid of slight conductivity, flowing down through the pipe 15, and through the lower port 16 connected with the space 13, through which the liquid flows upward and out through the port 17, into the pipe 18 connected with the tank 14. The liquid is circulated by the force pump 19, introduced 95 100

in the pipe 15. To control the pressure of the liquid the tank 14 is pressure tight, and is provided with the pressure gage 20, properly graduated to disclose the pressure 5 within the tank, or the pressure may be controlled by raising and lowering the tank.

In the present invention the liquid film circulating past the faces of the opposed electrodes is of slight electrical conductivity.

10 The liquids generally chosen for this purpose are the various forms of alcohol, alcoholic solutions, acetic acid or formaldehyde. The quantity of liquid exposed between the faces of the electrodes is reduced to the 15 minimum with respect to the superficial area of the electrodes exposed.

The holder 9 is provided with the stem 21, guided in the insulating bushing 22, fixed in the bracket 23, extending upward 20 from the base 24. This bracket has the extensions 25 and 26 fixed to the opposite ends of the electrode 1 by the screws 27 27, respectively. The length of the spark gap 13 is regulated by the adjusting screws 28—28 25 threaded in the insulating bushings 29 fixed in the bracket 23. The outer end of the stem 21 is provided with the insulating knob 30 fixed thereon. The expansion spring 31 is confined between the knob 30 and the 30 bushing 22, encircling the stem 21 and partially concealed within the recess in the knob 30. This arrangement of the mounting of the electrode 8 permits it to be pushed forward to contact, or approximately contact, with the electrode 1 for purposes that will be later described. The expansion of the spring 31 assists the internal pressure within the spark gap space 13, in restoring the electrode 8 to the normal position 35 abutting the ends of the adjusting screws 28, by the aid of which the length of the spark gap can be micrometrically adjusted, by screwing the adjusting screws in or out. The electrode 1 is provided with 40 the binding post 32 to receive the terminal 33. The electrode 8 is provided with a similar binding post 34 to receive the opposite terminal 35.

The operation and application of oscillators is presumed to be sufficiently well understood, so as not to require detail description of its particular position in the circuit, or the co-operative elements contributing to the results desired, in the art to which it 55 pertains.

This invention is operated substantially as follows:

The spark is started by pressing the knob 30 inward until the electrodes 1 and 8 are 60 brought into contact, which closes the circuit, starting the current flowing through the electrodes, creating a spark as they are separated, the length of the spark increasing as the electrode 8 returns to the normal

position fixed by the adjusting screws 28, 65 that regulate the fixed length of the spark for the desired purpose. It is important that this spark travel about, within the confines of the parallel area of the electrodes exposed to each other. 70

The instant that a spark jumps across the gap 13, the heat generated by the spark creates a bubble in the liquid confined between the electrodes. The point on one electrode from which the spark started, and the 75 point on the opposite electrode to which the spark jumped, are within the bubble for a sufficient period of time to prevent a second spark jumping across between the two exact surfaces isolated or insulated by the presence of the bubble. The succeeding sparks, (and they come in such rapid succession as to, for practical purposes, amount to a continuous flow) naturally choose points on the opposite electrodes not occupied by a bubble; therefore, the spark jumps about throughout the area of the opposing faces of the electrodes. The bubbles thus formed as described very slightly quench each 80 spark as it passes, preventing the formation of arcs at any point in the spark gap. This explanation is offered as a working hypothesis, and I do not wish to be understood as limiting the possibilities or the operation of 85 this invention thereto. 90

The slight conductivity of the liquid allows the sparks to pass between the faces of the electrodes, until said liquid becomes heated at the sparking points, producing 100 the bubbles as described. The action of the spark is practically continuous, regular and constant throughout the whole parallel surfaces of the electrodes, as is evidenced by the fact, that the negative carbon electrode is burned evenly and regularly throughout 105 its whole sparking area; this action is facilitated by the constant and regular speed and pressure of the film of liquid passing between the exposed faces of the electrodes. The structure illustrated prevents the forcing of sparks beyond the face of the electrodes, by undue speed in the flow of the liquid, owing to the fact that only the faces of the electrodes are exposed to the liquid. 110

The pressure and the flow of the liquid is 115 an important factor in accomplishing the results attained. In this description and the claims "confined pressure" is to be understood to mean greater than atmospheric pressure; therefore requiring containers, etc., not vented to the atmosphere at atmospheric pressure. The action of the electric current and the spark in a short time deteriorates the efficiency of this liquid, if the same quantity remains for any length of 120 time exposed between the electrodes. The constant confined pressure on the liquid tends to maintain a substantially uniform 125

density of the liquid between the electrodes, insuring a consequently uniform action of the spark and a more rapid and snappy travel of the same throughout the sparking area, due to the rapid circulation of the liquid; that also causes the rapid removal from the sparking area of any carbon or metallic particles given off by the electrodes, that may tend to accumulate and modify the action of the spark. Such particles, if any, would be precipitated within the tank and removed from the circulating liquid.

The liquid does not remain in the sparking area long enough to become electrolyzed, the electrolytic action being only partial. The constant circulation of the liquid also materially aids in carrying off the heat generated in the sparking area, thereby saving the electrodes from undue wear, and the liquid from a too rapid deterioration. The operation of the spark can be observed through the transparent glass wall 7.

Having thus described this invention what I claim and desire to secure by Letters 25 Patent is:—

1. An oscillatory spark gap apparatus of the character described including opposed electrodes, a wall surrounding said electrodes contiguous to the sparking areas thereof, and hermetically sealed thereto, said walls having inlet and outlet openings communicating with the space within said walls; means for circulating liquid through said space and across the faces of said electrodes 35 and for the escape of any gas or vapor which may be formed or generated between said electrodes.

2. An oscillatory spark gap apparatus of the character described including opposed electrodes, a wall surrounding said electrodes contiguous to the sparking areas thereof and hermetically sealed thereto, and means for circulating a liquid over and across the faces of the said electrodes under a regular constant and confined pressure.

3. A spark gap apparatus of the character described including opposed electrodes; a transparent wall surrounding said electrodes contiguous to the sparking areas thereof and hermetically sealed thereto; and means for circulating a liquid under confined pressure between said electrodes.

4. A spark gap apparatus of the character described, including a pair of opposed electrodes having parallel sparking surfaces; and means for confining a film of liquid under pressure between said sparking surfaces.

5. A spark gap apparatus of the character described, including opposed electrodes having flat parallel sparking planes; a transparent wall surrounding said planes contiguous to the sparking areas thereof;

and means for circulating a liquid under 65 confined pressure between said planes within said wall.

6. A spark gap apparatus of the character described, including opposed electrodes having flat parallel sparking planes; a 70 transparent wall surrounding said planes contiguous to the sparking areas thereof; means for adjusting one of said electrodes within said wall; and means for circulating a liquid under confined pressure between 75 said planes.

7. A spark gap apparatus of the character described, including an electrode having a sparking surface; a transparent wall surrounding said surface and hermetically engaging said electrode; an opposing electrode having a sparking surface and slideable within said wall; a packing interposed between said opposing electrode and said wall; 80 and a liquid confined within said wall, between said electrodes.

8. A spark gap apparatus of the character described, including an electrode having an annular wall; an opposing electrode slideably engaging said wall and having a stem; 90 a bracket attached to said first mentioned electrode and engaging said stem; adjusting screws threaded in said bracket and abutting said opposing electrode; and means for circulating a liquid within said wall.

9. A spark gap apparatus of the character described, including an electrode having a sparking surface; a hollow chamber behind said sparking surface, means for circulating a cooling medium through said chamber; an opposing electrode; a surrounding wall and means for hermetically sealing the contiguous edges of said electrodes to said walls; and means for passing a liquid 100 through said space.

10. A spark gap apparatus of the character described, including an electrode having an annular wall contiguous to and surrounding its sparking surface; ports through opposite ends of said sparking surface within said wall; an opposing electrode within said wall and a packing between said wall and said opposing electrode; and means for passing a film of liquid between said electrodes through said ports.

11. An oscillatory spark gap apparatus comprising aligned opposed interspaced electrodes, a sealing member inclosing the interspaced ends of the electrodes to form a chamber between the electrodes and to permit the opposite ends of said electrodes to project exterior of said sealing member, said sealing member having inlet and outlet openings formed therein and means for maintaining a circulation of liquid through said openings and the space or chamber formed between the electrodes.

12. An oscillatory spark gap comprising

- an inclosed casing having a chamber formed therein, and inlet and outlet openings, a stationary electrode projecting through one wall of said casing, a second electrode mounted in alinement with said first mentioned electrode projecting through an opposite wall of the casing, a flexible sealing member interposed between said electrode and said wall to permit movement of said second electrode with relation to said stationary electrode and means for maintaining a circulation of liquid through the inlet and outlet openings and the space formed between said electrodes.
13. An oscillatory spark gap apparatus comprising a pair of horizontally disposed electrodes having vertically opposed separated faces, a sealing member inclosing said opposed faces, said sealing member having an inlet opening in its lower side and an outlet opening in its upper side, and means for maintaining a circulation of liquid through said openings and the space formed between said electrodes.
14. An oscillatory spark gap apparatus comprising a pair of horizontally disposed electrodes having vertically opposed separated faces, a sealing member inclosing said opposed faces, said sealing member having an inlet opening formed in its lower side and an outlet opening in its upper side, a closed tank containing a liquid, pipes connecting the tank with the inlet and outlet openings and means for maintaining a circulation of liquid through said openings and the space formed between said electrodes.
15. The method of producing high frequency oscillating currents which consists in producing a spark discharge across a spark gap regulating the operation of the spark gap by passing a small body of liquid of relatively low conductivity between the electrodes confining said liquid under a controlled hydrostatic pressure thereby varying and regulating the condition of conductivity and resistance in said liquid and between said electrodes.
16. The method of producing continuous high frequency practically undamped oscillating currents, which consists in producing spark discharges across a spark gap regulating the passage of electrons between the electrodes of the spark gap by passing a small body of liquid of slight conductivity between said electrodes confining said liquid under a controlled hydrostatic pressure across and adjacent to the faces of said electrodes thereby varying and regulating the condition of conductivity and resistance in said liquid and between said electrodes.
17. The method of producing continuous high frequency practically undamped oscillatory currents in a spark gap which consists in producing spark discharges across a spark gap regulating the operation of the spark gap by passing a small body of liquid of slight conductivity between the electrodes confining said liquid under a controlled hydrostatic pressure across and adjacent to the faces of the electrodes and regulating the passage of electrons between the electrodes by removing the vapor and gas formed by the operation of said spark gap, from between and adjacent to said electrodes.
18. The method of producing alternating currents of high frequencies in a spark gap, which consists in producing spark discharges across a spark gap subjecting the faces of the electrodes of said spark gap to a liquid under confined controlled hydrostatic pressure.
19. The method of producing alternating currents of high frequencies in a spark gap which consists in producing spark discharges across a spark gap subjecting the faces of the electrodes of said gap to a circulating liquid which is maintained under a confined controlled hydrostatic pressure.
20. The method of producing alternating currents of high frequencies in a spark gap which consists in producing spark discharges across a spark gap passing a film of liquid between the faces of the electrodes and removing the gas and vapor generated between the electrodes.
21. The method of producing high frequency oscillating currents which consists in producing spark discharges across a spark gap regulating the operation of the spark gap by passing a small body of liquid of relatively low conductivity under controlled pressure between the electrodes in one direction only, thereby regulating the condition of conductivity and resistance in said liquid and between said electrodes.
22. The method of producing high frequency oscillating currents which consists in producing spark discharges across a spark gap regulating the operation of the spark gap by passing a small body of liquid of relatively low conductivity under controlled pressure between the electrodes in an upward direction only to regulate the condition of conductivity and resistance in said liquid and between said electrodes.
23. The method of producing alternating currents of high frequency which consists in producing spark discharges across a spark gap forcing a liquid under controlled pressure between the faces of the electrodes and confining said liquid between said electrodes, while the electrodes are connected in a circuit containing self induction and capacity.
24. The method of producing alternating currents of high frequency which consists in producing spark discharges across a

spark gap forcing a liquid under confined controlled pressure between interspaced electrodes, confining said liquid under a controlled hydrostatic pressure between the 5 electrodes, while the electrodes are connected in a circuit having self induction and capacity.

25. The method of producing alternating currents of high frequency in a spark gap, 10 which consists in producing a spark discharge across a spark gap and subjecting

the faces of the electrodes of said spark gap to a liquid under confined hydrostatic pressure.

In testimony whereof, I have hereunto set 15 my hand this twenty-seventh day of November, 1914.

ALFRED COHEN.
